[57] CLAIM

The ornamental design for an adjustable table, as shown.

DESCRIPTION

FIG. 1 is a perspective view of the adjustable table of my design;

FIG. 2 is a top plan view thereof;

FIG. 3 is a bottom view of the table;

FIG. 4 is a front elevational view thereof;

FIG. 5 is a rear elevational view thereof;

FIG. 6 is a left side elevational view thereof;

FIG. 7 is a front perspective view thereof showing the table in a raised position with the superimposed-petal surfaces in one position of opening;

FIG. 8 is a view similar to FIG. 7 showing the superimposed-petal surfaces in another position;

FIG. 9 is a perspective view thereof from the opposite side to FIG. 1 showing the table in a raised position with the superimposed-petal surfaces in another position;

FIG. 10 is a different perspective view thereof showing the table in a raised position with the superimposed-petal surfaces in yet another position;

FIG. 11 is a different perspective view thereof showing the table in a lowered position with the superimposed-petal surfaces in yet another position;

FIG. 12 is a still different perspective view thereof showing the table in a lowered position with the superimposed-petal surfaces in yet another position; and

FIG. 13 is a still different perspective view thereof showing the table in a lowered position with the superimposed-petal surfaces in yet another position.
